PERIODIC SIGNALING APPARATUS

Carl C. Chambers, Media, and Ralph M. Showers, Philadelphia, Pa., assignors, by mesne assignments, to the United States of America as represented by the Secretary of War

Application July 8, 1947, Serial No. 759,580

11 Claims. (Cl. 116—22)

1

The present invention relates to signaling apparatus, and particularly to a signaling device which will operate automatically and intermittently once the control mechanism is released.

In the discharge of canisters and other cargo from airplanes while in flight, as under wartime conditions, or in inaccessible territory at any time, it is highly desirable that some audible signaling device be associated with the packages so that they may be readily located by the intended receiver on the ground. It is also desirable that the signaling device continue to operate over a considerable period of time so as to afford the ground personnel sufficient opportunity to locate the package, and this without liability of attracting the attention of the enemy if wartime conditions prevail.

Accordingly, it is an object of this invention to provide an audible signaling device which will provide delayed action, i. e., will begin operation a substantial period of time after package to which it is attached has been released from the airplane.

It is a further object of the invention to provide a signaling device which will operate intermittently so as to conserve the use of the operating fluid and thus extend the period of time during which the signal may be sounded.

It is a still further object of the invention to provide a signaling device which may be repeatedly used from time to time by recharging the tank with compressed fluid which is used as the operating means.

Other objects and advantages of the invention will be apparent from the following description when taken in connection with the accompanying drawings in which:

Fig. 1 is a side elevational view of the complete apparatus with a side wall of the casing removed and parts shown in section;

Fig. 2 is an edge elevational view of the complete apparatus with part of the casing broken away;

Fig. 3 is a plan view of the encased apparatus with the interior construction shown in dotted outline.

Fig. 4 is an enlarged sectional view taken on the line 4—4 of Fig. 2; and

Fig. 5 is an enlarged horizontal sectional view taken on line 5—5 of Fig. 1.

The completely assembled signaling apparatus is disclosed in Figs. 1, 2, and 3, and the main features of the combination will be first described and then the detailed description of the controlling mechanism for the whistle or other audible

2

signal which may be employed in the combination.

The container, which is indicated by the numeral 1, is provided with a closure 1', and has mounted therein a main tank 2 for compressed fluids such as nitrogen, air, etc., and an auxiliary tank 3 which is shown in the present instance as surrounding the lower portion of the main tank 2. Associated with the upper end of the main tank 2 is a control mechanism 4, which constitutes the essence of the present invention, and to the interior of which are connected hose members 5 and 6 leading respectively to the auxiliary tank 3 and to a whistle 7 which extends to the exterior of the container 1 and is provided with a suitable guard 8. Straps 9 and 10 are mounted on the container exteriorly thereof and serve to secure the signaling apparatus to a canister or other type of cargo to be discharged from an airplane or the like, and a side wall of the container adjacent the upper end is provided with an opening through which extends a cord 11 for setting the control mechanism in operation, as will be described hereinafter. Also extending from the container 1, through an opening 12, is a cord 13 which is attached to the hose 6 through the medium of a clip 14 and serves to disconnect the hose by a pulling movement, thereby stopping the action of the whistle.

Referring now to the control mechanism, generally indicated by the numeral 4 and disclosed in detail in the enlarged sectional views of Figs. 4 and 5, the numeral 15 indicates a casing provided with a pressure chamber 16, through the central portion of which extends the solid integral web member 17 which is substantially narrower than the width of the chamber and thus permits communication between the upper and lower portions of the latter. Threaded into the side of the web portion 17 of the container is the main pressure tank 2, and communication between the interior of the tank and the pressure chamber 16 is provided by means of the transverse passage 18 and the longitudinal passage 19. The passage 18 also provides a means for recharging the tank 2, as will be later described.

Mounted within and adjacent the top of the pressure chamber 16 is a flexible diaphragm 20, the edges of the diaphragm being clamped to the casing by means of the closure 21 and bolts 22. Attached to the diaphragm 20 at its central portion is a threaded rod 23 which is also threaded to a sleeve 24 slidably mounted in an opening in the closure 21. A nut 24' is employed for locking the sleeve 24 to the rod 23. This sleeve is im-

ited in its downward movement by a U-shaped pin 25 which has connected to its outer end 26 the cord 11, heretofore referred to, which serves to initiate the operation of the whistle. A perforated block 27 is secured to the lower end of the rod 23 and supports a downwardly extending inverted U-shaped member 28, to the free ends of which is attached a crossbar 29. Threaded in the bar 29 is a screw 30, on the upper end of which is formed or mounted a cup 31 carrying a valve member 32 for normally closing the lower end of the vertical passage 19 of the web 17, the walls of the cup being provided with lateral openings 33 for facilitating communication between the passage 19 and the pressure chamber 16. It will be apparent from this arrangement that when the parts are properly adjusted, the valve 32 will prevent the escape of compressed fluid from the tank 2 into the pressure chamber 16. However, when the cord 11 is pulled, the pin 25 will be withdrawn and the sleeve 24 will be allowed to move relative to the closure 21 and thus lower the valve body 32 and permit the escape of the compressed fluid from the main tank 2 through the passageways 18, 19 and openings 33 into the pressure chamber.

As heretofore mentioned, the present signaling apparatus is provided with an auxiliary tank 3 and a hose 5 for providing communication between the two tanks. The hose 5 is connected to the nipple 5' which is threaded into the lower portion 36 of the casing and communicates with a chamber 34 formed in the lower end of the unit by means of complementary cavities formed in the closure 35 and an intermediate member 36 which are clamped to the casing by means of bolts 31. Communication between the interior of the nipple and the chamber 34 is provided by means of a passageway 38 formed in the member 36, and communication between the chamber 34 and the chamber 16 is provided by means of the vertical passageway 39 formed in the member 36. A flexible diaphragm 40, similar to diaphragm 20 in the chamber 16, is mounted in the lower chamber 34 by clamping its peripheral edge between the lower closure 35 and the body member 36, and the operation of the diaphragm is supplemented by an arched spring disc 41. This disc, which is provided with a central opening 42, is mounted upon a plate 43 which is fixed to the upper end of a hollow screw plug 44 threaded into and through the lower closure member 35. Within the plug 44 is a tubular member 45 which extends exteriorly of the plug and has a nipple 6 secured to its lower end, and which nipple is attached to hose 6 for conducting pressure fluid to the whistle 7 from time to time as permitted by the control mechanism.

The lower body member 36 is provided with a valve seat 46 centrally of its lower side, the valve seat being surrounded by an annular cavity 47 communicating with the pressure chamber 34 above the diaphragm 40, and the latter is provided with valve body 48 cooperating with the valve seat 46. Extending centrally through the valve body 48 is a small vertical passageway 49 which, at the proper time, permits the passage of pressure fluid to the opening 42 in disc 41 and thence through the tube 45 to the hose 6 and the whistle 7. Mounted at the bottom of the passageway 39, i. e., at the restricted portion thereof, is a flexible disc 50 provided with a central slit 51 which serves as a means for bleeding pressure fluid from the chamber 16 to the chamber 34. It will thus be seen that if pressure fluid is in cham-

ber 16 it will gradually bleed through the flexible disc 50 into the pressure chamber 34 and pass therefrom through the passage 38, nipple 5' and hose 5 into the auxiliary tank 3, and that if the pressure in tank 3 and chamber 34 becomes sufficiently great it will flex the diaphragm 40 and spring disc 41 downwardly so as to open valve 48 and permit the escape of the pressure fluid through the passageway 49, tube 45, and hose 6 to the whistle 7.

Means for recharging the main tank 2 with compressed fluid, after the signaling apparatus has been used and is being prepared for re-use, consists of a spring-pressed ball valve 52 mounted in a chamber 53 in the web member 17 and communicating with transverse passage 18 by means of apertures 54 formed in a disc 55 seated on the base of the chamber 53. This ball valve cooperates with a valve seat 56 formed at the inner end of a tube 57 threaded into the casing 15 and communicating with the chamber 53. The outer end of the tube 57 is of course provided with a suitable connection 58 by means of which a source of compressed fluid may be connected to the tube 57, thereby opening the valve 52 and passing through apertures 54 and passageway 18 into the interior of the main tank 2.

In the construction of this signaling apparatus, the diaphragm 20 is adjusted so that it will be flexed upwardly to close the valve 31, 32 when the pressure within the chamber 16 amounts to about 50 lbs., and the diaphragm and its related parts therefore serve as a pressure regulator to control the flow of pressure fluid from the tank into the chamber 16 to maintain 50 lbs. pressure therein after the latch for the valve has been released by pulling upon the cord 11; also, the diaphragm 40 and spring disc 41 are arranged to be operated when a pressure of about 25 lbs. is built up in the auxiliary tank 3 and chamber 34 by means of the bleeding action through the slotted disc 50. In this connection, it is to be noted that the passageway 49 is somewhat larger in cross-section than the slot in disc 50, and consequently when the valve 48 is opened pressure fluid will exhaust through the passageway 49 faster than it builds up in tank 3, with a consequent reduction in pressure in the chamber 34, thereby causing the valve 48 to close again. The arrangement and adjustment of the parts are therefore such that the valve 48 has a pulsating action, remaining open for about one second and closed for about three seconds while the pressure in the auxiliary tank 3 and chamber 34 again builds up to about 25 lbs.

As hereinbefore indicated, the present signaling apparatus is intended for use in connection with packages discharged from airplanes while in flight, and has for its purpose to provide an audible signal capable of being heard several hundred yards distant, and which will operate for a period of about twenty minutes so as to afford the intended receivers sufficient time to locate the particular article. To this end, the construction as hereinbefore described is so arranged that the signaling device will not operate for a period of about twenty seconds after it has been discharged from the airplane, i. e., about twenty seconds after the cord 11 is pulled. This period of inoperativeness of the whistle is caused by the time required for the pressure fluid to build up within the chamber 16 to a pressure of about 50 lbs. This pressure within the chamber 16, which is maintained at about 50 lbs. through the medium 75 of the pressure regulator 20, gradually bleeds

through the bleeder valve 50, 51 until about 25 lbs. pressure has built up in the auxiliary tank 3 and pressure chamber 34, and then the valve 48 is caused to open about every four seconds, one second being the period during which the whistle is blown and the other three seconds being the period of time required for the pressure to build up again to 25 lbs. to cause the whistle to be operated again. By adjustment of the parts, it will be readily understood that the various pressures referred to may be varied to suit particular requirements, and the amount of fluid initially placed in the tank 2 may be varied to permit a longer or shorter operation of the whistle. After the particular package has been recovered and the signaling device removed, the tank 2 may be recharged, as hereinbefore described, and placed in use from time to time as required.

In accordance with the patent statutes, we have described what we now consider to be the preferred construction of the signaling device, but it is obvious that various changes may be made therein without in any way departing from the spirit of the invention, and it is intended that all such changes be included within the scope of the appended claims.

We claim:

1. An audible signaling apparatus comprising a fluid-operated sounding device, a tank of fluid for operating the sounding device, releasable means for normally maintaining the apparatus inoperative, and means for delaying the operation of the sounding device after the releasable means is operated.

2. An audible signaling apparatus comprising a fluid-operated sounding device, a tank of fluid for operating the sounding device, means for automatically and intermittently feeding a portion of the fluid to the sounding device, releasable means for normally maintaining the apparatus inoperative, and means for delaying the operation of the sounding device after the releasable means is operated.

3. An audible signaling apparatus comprising a fluid-operated sounding device, a tank of compressed fluid for operating the sounding device, a supplemental tank communicating with first-mentioned tank, a pressure regulator for controlling the flow of fluid from one tank to the other, means for feeding pressure fluid from the second-mentioned tank to the sounding device, and releasable means for normally maintaining the apparatus inoperative.

4. An audible signaling apparatus comprising a fluid-operated sounding device, a pair of communicating tanks for containing compressed fluid, a pressure regulator for controlling the flow of pressure fluid from one tank to the second tank, another pressure regulator for controlling the flow of pressure fluid from the second of said tanks to the sounding device, and manually operable means for normally maintaining the apparatus inoperative.

5. An audible signaling apparatus comprising a fluid-operated sounding device, a casing provided with a pressure chamber, first and second fluid-pressure tanks adapted to communicate with said chamber, means for controlling the flow of fluid from one tank to the other, a pressure regulator for controlling the flow of fluid from the second tank to the sounding device, and manually operable means for normally maintaining the apparatus inoperative.

6. An audible signaling apparatus comprising

a fluid-operated sounding device, a casing provided with a pressure chamber, a pair of fluid-pressure tanks adapted to communicate with said chamber, a pressure regulator for controlling the flow of fluid from one tank to the pressure chamber, means for bleeding pressure fluid from the chamber to the other tank, a pressure regulator for controlling the flow of fluid from the last-mentioned tank to the sounding device, and manually operable means for normally maintaining the apparatus inoperative.

7. An audible signaling apparatus comprising a fluid-operated sounding device, a casing provided with a pressure chamber, a main fluid-pressure tank and an auxiliary fluid-pressure tank adapted to communicate with said chamber, pressure regulators for controlling the flow of fluid from the main tank to the auxiliary and from the last-mentioned tank to the sounding device, and valved means for charging the main tank with fluid pressure.

8. An audible signaling apparatus comprising a fluid-operated sounding device, a casing provided with a pressure chamber, a main fluid-pressure tank and an auxiliary fluid pressure tank adapted to communicate with said chamber, and pressure regulators for controlling the flow of fluid from the main tank to the auxiliary tank and from the last-mentioned tank to the sounding device.

9. An audible signaling apparatus comprising a fluid-operated sounding device, a casing provided with a pressure chamber, a main fluid-pressure tank and an auxiliary fluid pressure tank adapted to communicate with said chamber, pressure regulators for controlling the flow of fluid from the main tank to the auxiliary tank and from the last-mentioned tank to the sounding device, and releasable means for normally maintaining the apparatus inoperative.

10. An audible signaling apparatus comprising a fluid-operated sounding device, a casing provided with a pressure chamber, a main fluid-pressure tank and an auxiliary fluid pressure tank adapted to communicate with said chamber, pressure regulators for controlling the flow of fluid from the main tank to the auxiliary tank and from the last-mentioned tank to the sounding device, and a bleed valve between the pressure chamber and auxiliary tank.

11. An audible signaling apparatus comprising a fluid-operated sounding device, a casing provided with a pressure chamber, a main fluid-pressure tank and an auxiliary fluid pressure tank adapted to communicate with said chamber, pressure regulators for controlling the flow of fluid from the main tank to the auxiliary tank and from the last-mentioned tank to the sounding device, a bleed valve between the pressure chamber and auxiliary tank, and releasable means for normally maintaining the apparatus inoperative.
